2 SHEETS—SHEET 2.

UNITED STATES PATENT OFFICE.

NORMAN B. HURD, OF NEW BRITAIN, CONNECTICUT, ASSIGNOR TO THE AMERICAN HARDWARE CORPORATION, OF NEW BRITAIN, CONNECTICUT, A CORPORATION OF CONNECTICUT.

LOCK.

1,168,725.

Specification of Letters Patent. Patented Jan. 18, 1916.

Application filed October 23, 1915. Serial No. 57,405.

To all whom it may concern:

Be it known that I, NORMAN B. HURD, a citizen of the United States of America, residing at New Britain, Connecticut, have 5 invented a new and useful Lock, of which the following is a specification.

My invention relates to improvements in locks, the object being to provide certain new and useful features whereby certain 10 new functions may be effected which are of particular utility in connection with certain types of locks, for example, locks such as used in the exit doors of public buildings or stores where it is desired to lock the door 15 from the outside at night, and where it may be desirable during the day to not only leave the door unlocked, but to hold retracted the latch bolt so that in the case of emergency such as fire, panic or the like, the 20 door may be freely swung open. These and other advantages will be apparent to the mechanic skilled in the art from an examination of the accompanying drawings, and a reading of the following description.

25 In the drawings: Figure 1 is a face or edge view of the lock. Fig. 2 is a side elevation with the cap plate of the case removed to show the internal lock works. Fig. 3 is a relatively enlarged end view of a cylinder lock of a form which it is preferred to use 30 with the lock work. Fig. 3a is a vertical sectional view through the center of Fig. 3, showing certain parts in elevation. Fig. 4 is a section on the line 4—4 of Fig. 2. Fig. 35 5 is a view of certain parts of the lock work mechanism in a different position from that shown in Fig. 2. Fig. 6 is a similar view with the parts in still another position. Figs. 7 and 8 are views of keys.

40 In the particular form of the invention as shown in the drawings, I have elected to illustrate my improved features as associated with the various parts of a so-called mortise lock, although the invention is not limited to that particular type. So also I have elected to show one preferred form of my invention which it will be obvious is capable of modification in many respects.

1 represents the face plate of a lock.

2 represents the lock case.

3 is the locking bolt. In this instance said locking bolt is of the spring latch type.

4 represents what is commonly known as a

controller, the well known function of the same being, when repressed, to cause certain 55 dogging mechanism to block repression of the bolt 3 by a tool inserted along the face 1 of the lock. In this instance the controller 4 operates the swinging latch dog 5.

6 is a roll-back mounted in the case 2 and 60 in this instance arranged to be operated by the knob spindle 7.

8 is a key controlled latch retracting lever which is pivotally mounted at 9 in the lock case. The lower end of this lever 8 engages 65 with a plate 10 carried by the tail of the latch bolt, while the upper end of said lever is provided with an arm 11 which may be engaged by a suitable key or key controlled means, one form of which will later be described, whereby when the key is turned the latch may be retracted, even though the knob roll-back 6 may be then locked or dogged.

12 is a dog for the roll back 6, the same 75 being movable into and out of the dogging position. In Fig. 2 the dog 12 is shown as overstanding part of the roll-back 6 so as to prevent the same from being turned in the latch retracting direction. In Figs. 5 and 6 80 this dog 12 is shown in the "off" position wherein the roll-back 6 is free to be turned by the knob spindle 7, which in this particular instance is located on the out door side of the lock. The dog 12 may have a suitable 85 support or guide, as shown, and may be suitably held in the "on" and "off" position as by a friction spring 13. The upper end of the roll-back 6 in the particular form shown engages with the tail plate 10 of the latch 90 bolt so that when the roll-back 6 is turned, it will retract the bolt 3 as shown in Fig. 5.

14 is another roll-back which is pivoted at 15 in the case 2. In this particular form, this roll-back 14 is rocked on its pivot 15 by 95 a manually operable member 16, located on the indoor side of the lock. When this part 16 is lifted the roll-back 14 is swung. The upper end of this roll-back 14 engages the tail plate 10 of the latch indirectly through 100 the medium of the lower end of the lever 8, although this is perhaps not essential in all forms. When the part 16 is moved properly, the roll-back 14 swings and retracts the latch.

As to the parts thus far described, no nov-

elty, broadly speaking, is claimed. The novelty resides in those parts about to be described, wherein the main objects, related at the outset, may be attained.

Referring particularly to Figs. 5 and 6, attention is directed to the rocking member 17 pivoted at 9 and located adjacent to the inner end of a cylinder lock C, which is secured to the case 1 on the outdoor side thereof in the usual manner. This rocking member 17 carries a downwardly directed arm 19, which in turn carries a pin 20. This pin 20 projects into a cam groove 21 in an arm 22. One end of this arm 22 is pivotally supported at 23 on the upper end of a lever 24 which in turn is pivotally supported at 25 in the lock case. The lower end of the lever 24 makes a suitable connection with the dog 12 so that as the lever 24 is rocked to and fro the dog 12 will be projected and retracted. The other end of the arm 22 is, at certain times, located above the tail plate 10 of the latch bolt (see Fig. 6), and at other times may be dropped to a position in front 25 of the tail 10 (see Fig. 5). 26 is a shoulder on the lower side of the arm 22 which at certain times is permitted to project down behind a shoulder 27 fixed within the lock case (see Fig. 5) and at other times may stand slightly above said shoulder (see Fig. 6). The usual springs may be provided wherever desirable, for example, 28 is a spring normally operating in a direction to lift the rear end of the arm 22, and 29 is the usual spring provided to project the latch bolt 3. 30 is the usual spring for the controller 4. 31 is the usual spring for the latch dogging member 5. The cylinder lock C in this particular instance, is preferably 35 constructed substantially as set forth in a former Patent No. 1,115,040, dated Oct. 27, 1914, and has a fixed roll-back arm 32 and a second roll-back 33. The roll-back arm 32 is designed in this instance to act upon 40 the lever 8 so as to retract the latch bolt should the outside knob roll-back 6 be dogged (see Fig. 2). This roll-back 32 is mounted on the usual cylinder lock plug and is operated by an ordinary key 34. At 45 such times the roll-back 33 is held in an ineffective position. If, however a special key, which might be termed an "emergency key" or a "proprietor's key" such as indicated in 35, (Fig. 7) is inserted, it will move 50 the roll-back 33 into its effective position where when the key is turned it will operate upon the rocking member 17. Assuming such a key 35 were used, and turned in the direction indicated in Fig. 5, the roll-back 55 33 would encounter the right hand end of the rocker 17, and if the latch were at that time retracted, as shown in Fig. 5, the tilting of the rocking member 17 would cause the right hand end of the arm 22 to move

down in front of the latch tail plate 10, thus holding the latch retracted. If, on the other hand the latch should not be retracted at such a time, the depression of the right hand end of the lever 17 could not depress the arm 22, but the latter would have to slide to the left which would cause the lever 24 to shift the dog 12 to the position indicated in solid lines Fig. 2, and dotted lines, Fig. 6. If the key were turned in the opposite direction, the roll back 33 would engage the other end of the rocking member 17 and shift it from the position indicated in Fig. 2 to the position indicated in Fig. 6, thus again sliding the arm 22 to the right and swinging the lever 24 so as to withdraw the dog 12. By this means it is within the power of the holder of the key 35 to lock the door against entry from the outside through the medium of the knob spindle 7, although at such a time access could be gained through the medium of a proper key such as 34, which would retract the latch by means of the lever 8. The holder of the emergency key 35 may also lock the latch 3 retracted as shown in Fig. 5, should there be any occasion therefor.

It is obvious that when the door is supposed to be unlocked it would be desirable to have the latch dog 5 in the latch disengaging position. Accordingly, I preferably provide on the dog 5, an incline 36 which may be engaged by the projecting end of the pivot pin 23 at the upper end of the lever 24, which, when said lever 24 stands in the position indicated in Fig. 6 will engage the incline 36 and hold the latch dog 5 lifted. Should the roll back dog 12 be thrown to the "on" position (Fig. 2) the latch dog 5 is controlled by the controller 4, that is to say, when the door is open the latch dog 5 will be lifted to permit the latch 3 to spring back when the door is closing. When the door is fully closed and the controller 4 is repressed by engagement with the edge of the door, the latch dog 5 will drop behind the latch bolt 3 to perform its function in the usual manner.

When, as in the preferred form shown herein, the key is of the usual type associated with a cylinder lock and is arranged to engage indirectly the internal mechanism through the medium of roll-back mechanism, and when I provide an auxiliary roll-back such as indicated at 33, the latter may be mounted upon a slide 33^a (Fig. 3^a) which slides in the roll-back portion 32. When so constructed, the insertion of the key 35 will engage the slide 33^a so as to push the roll-back 33 outwardly against the tension of the return spring 33^b, in which position the roll-back 33 will perform its aforesaid functions. This is a preferred form of construction corresponding in these details, as I have be-

fore said, with the construction set forth in a former Patent No. 1,115,040.

By making the latch hold back means independent of the latch retracting means, there is no danger of inadvertently or accidentally locking back the latch when it is intended merely to retract the latch. Again, by the new arrangement of parts herein disclosed I am enabled to use a common key

10 passage located at the outdoor side of the lock for admitting both of the keys by which the several internal lock parts are controlled.

As stated at the outset, I have shown my invention only in one preferred form fully 15 appreciating that a wide variety of modifications may be made by a mechanic skilled in the art without departing from the spirit and scope of the invention as disclosed and claimed.

20 What I claim is:

1. In a lock, a movable latch bolt, means for projecting the same, means for retracting the same, means operable by a key for operating said retracting means, and means independent of said retracting means to lock said latch bolt in its retracted position by the same key.

2. In a lock, a case, a latch bolt movable to and fro therein, yielding means for normally 30 projecting said bolt, means for retracting the latch bolt through the medium of a key, and means independent thereof for holding said latch bolt in its retracted position by the operation of said key.

3. In a lock, a case, a latch bolt movable therein, means for normally projecting the latch bolt, said case having a key-passage, means operable by a key adapted to retract the latch, and means independent thereof for holding said latch in its retracted position by the operation of a key through said afore- 40 said key passage.

4. In a lock, a case, a cylinder lock, a latch bolt movable therein with means for yieldingly projecting said bolt, means for retracting said bolt, means independent of said retracting means for holding said bolt retracted, with means carried by said cylinder lock and operable by a key for controlling 45 the operation of the latch retracting means and the latch holding means.

5. In a lock, a case, a normally projected spring latch bolt mounted therein, a device mounted in said case and movable therein for retracting the latch, another device also mounted in said case and independent of the latch retracting device for holding the latch retracted, with a key controlled means for operation of either of said devices.

60 6. In a lock, a case, a normally projected spring latch bolt mounted therein, a device mounted in said case and movable therein for retracting the latch, another device also mounted in said case and independent of the

latch retracting device for holding the latch 65 retracted, with a key controlled means for operation of either of said devices, said means comprising a cylinder lock having two roll back elements, one of said roll back elements being movable relatively to the 70 other, both of said roll backs being movable simultaneously.

7. In a lock, a latch bolt, means for yieldingly projecting the same, a key operated means for retracting the latch, an independent hand-operated means for retracting the latch, means for dogging the latter against movement in the latch retracting direction, means independent of the lock retracting means capable of holding back the latch 80 when the latter stands retracted, and a key operable device for operating the dogging means when the latch is projected, and for operating the latch hold back means when the latch stands retracted.

8. In a lock, a latch bolt, means for yieldingly projecting the same, a key operated means for retracting the latch, an independent hand-operated means for retracting the latch, means for dogging the latter against 90 movement in the latch retracting direction, means capable of holding back the latch when the latter is retracted, and a key operable device for operating the dogging means when the latch is projected, and for operating the latch hold back means when the latch is retracted, said key operable means including an arm connected at one end to said dogging means, and blocked against descent at the other end by the inner end of 100 the latch bolt when the latter is projected, said latch bolt moving clear of said arm when it is retracted, whereby said arm may be moved into a position to engage and hold said latch retracted.

9. In a lock, a latch bolt, a key operable means for retracting the latch from the outdoor side of the lock, a handle for retracting said latch also from the outdoor side of said lock, a dogging means for the latter to prevent the retraction of the latch by the handle, said dogging means being also key-operable from the outdoor side of the lock, means independent of the latch retracting means for holding back said latch when re- 115 tracted, said means being also key-operable from the outdoor side of the lock, said latch hold-back means being independent of the latch retracting means.

10. In a lock, a latch bolt, a key operable 120 means for retracting the latch from the outdoor side of the lock, a handle for retracting said latch also from the outdoor side of said lock, a dogging means for the latter to prevent the retraction of the latch by the handle, said dogging means being also key-operable from the outdoor side of the lock, means independent of the latch retracting

means for holding back said latch when retracted, said means being also key-operable from the outdoor side of the lock, said latch hold-back means being independent of the latch retracting means, and being dependently associated with said dogging means.

11. In a lock, a case, a spring latch bolt removable therein, a key-operable lever for retracting the latch, a spindle operable lever for retracting the latch, a dogging means for the latter, a hold back device for the latch when the latter is retracted, said hold-back device being operatively connected with said dogging means and independent of the latch retracting means, said hold-back device being movable in one direction to operate the dogging means, and in another direction to hold back the latch, and a key controlled means for imparting movement 20 to said hold-back means in both of said directions.

12. In a lock, a case, a spring latch bolt removable therein, a key operable lever for retracting the latch, a spindle operable lever for retracting the latch, a dogging means for the latter, a hold-back device for the latch when the latter is retracted, said hold-back device being operatively connected with said dogging means and independent 25 of the latch retracting means, said hold-back device being movable in one direction to operate the dogging means, and in another direction to hold back the latch, and a key controlled means for imparting movement 30 to said hold-back means in both of said directions, said key operable means including a tilting member operatively connected with said roll-back device, and also including a cylinder lock having a rotatable 35 plug, and roll-back mechanism mounted on said plug and operating on said tilting member when the plug is turned by one key and also capable of operating on said latch retracting means without effecting said tilting member when said plug is turned by a 40 different key.

13. In a lock, a case, a spring latch bolt mounted therein, key controlled means also mounted therein for retracting the latch bolt, and key-controlled means independent of said retracting means to hold back said latch in its retracted position, said retracting means and hold-back means being operable by different keys, said case having 55 a passage in common to both of said keys.

14. In a lock, a case, a spring latch bolt mounted therein, key controlled means also mounted therein for retracting the latch bolt, and key-controlled means independent 60 of said retracting means to hold back said latch in its retracted position, said retracting means and hold-back means being operable by different keys, said case having a

passage in common to both of said keys, and pin tumbler mechanism arranged to be 65 operated by both of said keys.

15. In a lock, a case, a spring latch bolt, two independent means at the outdoor side of said case for retracting said latch, one of said means being key-operable, a key 70 operable dog for preventing the retraction of the latch by the other means, a latch hold-back mechanism independent of the retraction means but also operable by the same key designed to operate said dogging 75 means, said dogging means and said hold-back means being moved into the dogging position and the hold-back position respectively by the rotation of said key in the same direction, said hold-back means being 80 movable into the latch hold-back position only when the latch bolt has been previously retracted.

16. In a lock, a case, a spring latch bolt therein, two independent means at the outdoor side of said lock, for retracting said latch, one of said means being key-operable, a dogging device for the other retracting means, said dogging device being key-operable, a hold-back means to hold the latch 90 retracted, said hold-back means being also key-operable and comprising a movable arm operatively associated with said dogging means for moving the latter by said key when the latch is projected, said arm being 95 movable in the latch hold-back direction only when said latch bolt has been previously retracted.

17. In a lock, a case, a spring latch bolt mounted therein, means at the indoor side 100 of the latch case for retracting the latch at all times, two independent means at the outdoor side of said case for retracting said latch, one of said last mentioned retracting means being key-operable, a dog for stopping the operation of the other retracting means, said case having a key passage on the outdoor side, means for holding the latch bolt retracted, said means being independent of the retracting means, one key 105 operating through said key passage to retract the latch, another key operating through said key passage to hold the latch retracted after said latch has been previously retracted.

18. In a lock, a case, a spring latch bolt mounted therein, means at the indoor side of the latch case for retracting the latch at all time, two independent means at the outdoor side of said case for retracting said latch, one of said last mentioned retracting means being key-operable, a dog for stopping the operation of the other retracting means, said case having a key passage on the outdoor side, means for holding the latch 110 bolt retracted, said means being independent 115 of the retracting means.

of the retracting means, one key operating through said key passage to retract the latch, another key operating through said key passage to hold the latch retracted after 5 said latch has been previously retracted, said hold-back means comprising a member movable in two directions, said member be-

ing operatively connected with said dogging means whereby when moved in one direction it will operate said dogging means and when 10 moved in another direction it will engage and hold back the latch.

NORMAN B. HURD.
